No. 15,029

9192

9192

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,029, dated May 27, 1884.

Application filed March 27, 1884. Term of patent 33 years.

To all whom it may concern:

Be it known that I, LOUISE TULLY, of the city, county, and State of New York, have invented and produced a new and original Design for a Pattern of a Lady's Costume, (numbered 9,192;) and I do hereby declare that the engraved prints accompanying this specification convey to any one accustomed to using paper patterns a clear understanding of how a garment made up by the pattern will appear.

The design shows a round walking-skirt and a basque. The skirt exhibits a drapery crossing the front in *tablier* fashion, falling in deep points at the back and displaying gatherings at the sides, and box-plaited side panels extending the full depth of the skirt and having the appearance of overlapping the sides of the

drapery. The basque exhibits closely-fitted under fronts displaying buttons all the way down, closely-fitted jacket-fronts rounding away from the throat, a closely-fitted back displaying a draping at the lower part of the center and falling in two points, coat-sleeves exhibiting their lower parts reversed in cuffs, and a standing collar.

What I claim as my invention, and desire to secure by Letters Patent, is—

The design for a lady's costume, as shown in the engraved prints accompanying this specification.

LOUISE TULLY.

Witnesses:

ALFRED FRANCIS,
JOHN HENRY DRURY.
